(57) **CLAIM**

The ornamental design for a cosmetic brush handle, as shown and described.

DESCRIPTION

FIG. 1 is a front perspective view of the cosmetic brush handle showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a cross-sectional view of the cosmetic brush handle taken along the line 8-8 in FIG. 6;

FIG. 9 is a perspective view showing the cosmetic brush handle as it would appear with the bristles inserted; and,

FIG. 10 is another perspective view showing the cosmetic brush handle as it would appear with the bristles inserted. The broken line showing of brush bristles in the drawings illustrates environmental structure and forms no part of the claimed design.
